CIGARETTE CASE

Filed June 30, 1930

INVENTOR:

CHARLES PICKER
by Andrew Lewis
His ATTORNEYS

UNITED STATES PATENT OFFICE

CHARLES PICKER, OF ALBANY, NEW YORK

CIGARETTE CASE

Application filed June 30, 1930. Serial No. 464,902.

My invention more particularly relates to a case for cigarettes or the like which may be made liquid tight so that it may be worn by a bather, and which is preferably provided with a lighter for the cigarettes. The device is particularly useful for bathers, as it may readily be attached to the clothing and readily opened while the bather is in the water and a cigarette removed from the case and lighted and the case again closed. My invention provides a cheap, compact, and effective device of the character above described.

My invention will best be understood by reference to the accompanying drawings, in which I have illustrated a preferred embodiment of my invention, and in which—

Fig. 1 is a vertical, sectional view through a cigarette case, embodying my invention.

Fig. 2 is an end view of the device with the cover removed.

Fig. 3 is a section taken along the line 3—3 of Fig. 4.

Fig. 4 is a section taken on the line 4—4 of Fig. 3.

Fig. 5 is a side view of a clamp for securing the case to the clothing, and

Fig. 6 is a plan view of Fig. 5.

Like reference characters indicate like parts throughout the drawings.

Referring now to the drawings, 10 indicates generally a case comprising side-walls, 11, and a bottom wall, 12, which forms a liquid tight joint with the side walls and is preferably integral therewith, as illustrated, the side walls and the bottom wall forming a chamber, 13, for the reception of cigarettes or the like.

In the embodiment of my invention illustrated, a partition, 14, extends transversely across the middle portion of the casing and is preferably formed integral therewith, as best shown in Fig. 4. The partition member, 14, extends upwardly to a point, 16, which is short of the top of the side walls of the case, as indicated in Fig. 3, and is provided with an opening, 15, extending vertically therethrough. An extension or stem, 17, extends upwardly from the partition, the same preferably being contracted, as at 18.

The opening, 15, in the partition which extends also through the stem, 17, is adapted to contain liquid fuel and a wick, which is provided with an exposed end, 20, in the manner usual for a cigarette lighter.

Preferably the entire case, together with the partition member and the lower portion of the stem, 17, is molded from bakelite, or like material, and a metallic member, 21, which is provided with screw threads, 19, is suitably secured in the upper end of the stem, 17, as indicated at 22.

The cover for the device is indicated at 23, the major portion of which may also be formed of bakelite and the edge of which is preferably provided with a downwardly and inwardly extending flange, 24, surrounding the upper edge of the side walls of the case.

The cover comprises a clamping member, 25, preferably formed of bakelite, the clamp being rotatable with respect to the cover proper. The clamp, 25, is preferably provided with a metal insert, 27, having an opening, 29, provided with screw threads, 30, engaging the screw threads on the upper end of the stem, 17, the metal insert preferably being provided with a flange, 26, engaging the lower side of the cover, 23. The upper portion of the clamping member, 25, is preferably knurled as at 28.

By placing the cover in position over the end of the case and turning the member, 25, the cover may be brought into liquid tight engagement with the upper edge of the side walls of the case. A gasket, 251, is interposed between the clamp, 25, and the cover, 23, to form a liquid tight joint between the two.

A lighter, indicated generally at 31, is also provided and comprises a wheel, 32, mounted on a shaft, 33, in a yoke, 34, formed at the upper end of a stem, 35.

The partition, 14, is provided with an opening, 36, for the reception of the stem, 35, of the lighter. The opening, 36, is preferably T shaped in cross section, as best shown in Fig. 4, and the stem, 35, of the lighter is preferably rectangular in cross section. One portion, 361, of the opening, 36, is parallel to the side walls of the case, 10, and extends to the bottom, or nearly to the bottom of the

case, as indicated in Fig. 3. When the stem of the lighter therefore, is placed in the portion, 361, of the opening, the lighter is lowered to a position where the wheel, 32, is located beneath the cover, 23, so that the case is liquid tight and the lighter and the cigarettes are housed within the case.

The opening, 36, is also provided with a portion, 362, disposed at right angles to the portion, 361, and this portion of the recess extends downwardly only to a point, 37, which is sufficiently above the lower end of the recess, 361, to bring the wheel, 32, opposite the exposed end, 20, of the wick. It will, of course, be understood that the lighter is provided with the usual flint (not illustrated) for producing a spark.

A clamp, 371, as best shown in Figs. 5 and 6, is preferably provided for securing the cigarette case to the clothing of the bather. The clamp is provided with end portions, 38, which are adapted to slip over the edges of the case into the position indicated in Fig. 2. In the embodiment illustrated, a tongue, 39, is stamped from the sheet metal of the clamp and by pulling the tongue, 39, away from the body portion of the clamp, and inserting a portion of the clothing between the tongue and the main body of the clamp, the case may be secured to the clothing of the bather. The bottom, 12, of the casing is preferably provided with a flange, 121, which, with the cover flange, 24, prevents the clamp, 371, from slipping off from the casing.

The lower portion of the wall surrounding the chamber, 15, is preferably provided with a metal insert, 40, of the character indicated in Fig. 1. The interior of this member, 40, is threaded and is adapted to receive the threaded stem of a screw cap, 41, and thereby close the lower end of the opening. A gasket, 42, is preferably interposed between the flanged portion of the screw cap and the bottom of the recess, 43, in which said flange is received. By inverting the case, the chamber, 15, may be filled with a suitable fuel.

The operation and use of my invention will readily be understood from the foregoing description, and is as follows: Assuming that the cover of the device is removed, the cigarette case is filled with a desired number of cigarettes, and the lighter, 31, is inserted in the portion, 361, of the opening, 36, and is depressed to the full line position indicated in Fig. 3. The cover is then placed in position over the top of the case, and by screwing the clamping member, 25, over the threaded end, 19, of the stem, 21, the cover is brought into liquid tight engagement with the upper edge of the side walls of the case to form a liquid tight engagement therewith. The clamp, 37, is then attached to the clothing. When the bather desires to smoke a cigarette, he first turns the clamp, 25, and then removes the cover from the case. The

cigarette is then taken and lighted by lifting the lighter, 31, from the portion, 361, of the opening, 36, and turning it at right angles and inserting the stem in the portion, 362, of the opening to the position indicated in Fig. 3, and turning the wheel, 32, in the usual manner, a spark is produced.

While I have illustrated the main portion of the case as formed of bakelite, it will, of course, be understood that it may be formed of metal or any other desired material.

It will likewise be understood that, while I have illustrated a fuel containing member extending upwardly through said casing and through the cover, a plain member could thus extend upwardly through the cover, a clamp engaging the upper end of the member and securing the cover in liquid tight engagement with the upper edges of the walls of the case.

While I have described my invention in its preferred embodiment, it is to be understood that the words which I have used are words of description rather than of limitation and that changes within the purview of the appended claims may be made without departing from the true scope and spirit of my invention in its broader aspects.

What I claim is—

1. In a case for cigarettes or the like, a removable cover, a tubular member attached to said case and adapted to contain liquid fuel and a wick, said tubular member extending upwardly above said case, means engageable with the upper end of said tubular member for clamping said cover in liquid tight engagement with the top of said case, and a lighter normally housed within said case.

2. In a case for cigarettes or the like, comprising a removable cover, a tubular member secured to said case and adapted to contain liquid fuel and a wick, said tubular member extending upwardly above said case, means engageable with the upper end of said tubular member for clamping said cover in liquid tight engagement with the top of said case, and a lighter adapted to be housed in said case, said lighter being readily removable from said case to a point adjacent to the exposed end of said wick.

3. In a case, the combination of side walls and a bottom wall forming a liquid tight connection therewith, said walls enclosing a chamber adapted to receive cigarettes or the like, of a hollow member secured to said bottom wall and extending upwardly above said side walls, means comprising the upwardly extending end of said hollow member for clamping said cover into liquid tight connection with the upper edges of said side walls, said hollow member being adapted to receive liquid fuel and a wick, and a lighter adapted normally to be housed in said case, and means for holding the end of said lighter

adjacent to the end of said wick when said cover is removed.

4. In a case, the combination of a case comprising side walls and a bottom wall forming a liquid tight connection therewith, a cover for said casing, said walls enclosing a chamber adapted to receive cigarettes or the like, of a hollow member secured to said bottom wall, the end of said stem extending above the upper edge of said side walls, a wick located in said hollow member and extending upwardly to the end of said member, a sparking device provided with a stem, and means attached to said case and provided with a recess having two portions of different depths adapted to receive said stem in two different angular positions and to retain said sparking device within said casing and in a position opposite the exposed end of said wick, respectively.

5. In a case, the combination of a case comprising side walls and a bottom wall forming a liquid tight connection therewith, said walls enclosing a chamber adapted to receive cigarettes or the like, of a hollow member secured to said bottom wall and extending upwardly above said side walls, means comprising said hollow member for clamping said cover into liquid tight connection with the upper edges of said side walls, said stem being adapted to receive liquid fuel and a wick, the bottom of said stem being provided with an opening, through which said stem may be filled with fuel, a liquid tight closure for said opening, a sparking device, and means for retaining said sparking device within said casing in a given position when said cover is clamped in position, and for retaining said sparking device opposite the exposed end of said wick when the cover is removed.

CHARLES PICKER.
